TAPE SMOOTHING MACHINE

Walter C. George, St. Louis, Mo., assignor to
 Gaylord Container Corporation, St. Louis, Mo.,
 a corporation of Maryland

Application August 1, 1938, Serial No. 222,350

12 Claims. (Cl. 93—56)

This invention relates to machines for pressing and smoothing out gummed tape upon folded paper box blanks or other articles after being manually or mechanically applied thereto. The invention has for its principal objects to obtain complete adhesion of the tape free from blisters and wrinkles; to prevent slippage of the taped article on the conveyer during the tape smoothing operation; to provide for adjusting the pressure of the tape smoothing devices on the tape; to enable the machine to accommodate articles of different thicknesses; to provide for varying the speed relation between the article conveying tape smoothing devices; and to adapt the machine for operation in proper timed relation with an automatic taping machine. The invention consists in the tape smoothing machine and in the construction, combinations and arrangements of parts hereinafter described and claimed.

In the accompanying drawings, which form part of this specification and wherein like symbols refer to like parts wherever they occur:

Fig. 1 is a side elevational view of a tape smoothing machine embodying my invention,

Fig. 2 is a view of the article receiving end of the machine,

Fig. 3 is an enlarged fragmentary side view of the machine in the region of the tape brushes and pressure rolls therefor,

Fig. 4 is a vertical transverse section on the line 4—4 in Fig. 1;

Fig. 5 is a perspective view of a folded box blank, showing the tape applied thereto over the meeting edges thereof; and

Fig. 6 is a diagrammatic side elevational view, showing the variable speed drive connection between the tape smoothing machine and a machine for automatically affixing the tape to the article and for feeding the taped article to said tape smoothing machine.

The machine illustrated in the accompanying drawings is particularly adapted for use in smoothing out a strip A of gummed tape upon a folded paper box blank B to secure the parts thereof together or to strengthen a joint. Said machine comprises a frame C made up of outwardly facing channel-shaped side and end frame members 1 and 2, upstanding brackets 3 and 4 secured to the ends of the respective front and rear end frame members and to the front and rear tops of pedestals 5 and 6 located beneath the corresponding ends of the side frame members and longitudinal tie and strut members 7 connecting said front and rear pedestals. An end-

less article conveying and drying belt 8 extends longitudinally of the frame C below and intermediate between the side rails 1 thereof and passes around a driving pulley 9 at the rear or delivery end of the machine and a driven pulley 10 at the front or receiving end thereof. The driving pulley 9 is fixed to a cross-shaft 11 whose ends are journaled in suitable bearings 12 provided therefor in the rear pair of pedestals 6. The driven pulley 10 is rotatably supported on a cross-shaft 13, whose ends are non-rotatably supported in pockets or recesses 14 provided therefor in the front pair of pedestals 6. The driven pulley shaft 10 is adjustable towards and away from the driving pulley shaft 13, to vary the tension of the conveyer belt 8, by means of screws 15 that are threaded through the front pair of pedestals 5 in abutting relation to said driven pulley shaft. The conveyer belt 8 is made of suitable friction producing material adapted to resist slippage of the articles thereon.

The mechanism for smoothing out the gummed tape A affixed to the box blank B comprises a set of floating pressure rolls 16 that are disposed above and crosswise of the rearwardly traveling upper stretch of the conveyer belt 8 at the receiving end thereof with their ends journaled in horizontal bars 17, whose rear ends are anchored to the respective side rails 1 of the frame C by means of links 18. These rollers serve to press the tape down on the box during the initial setting of the glue. The taped article then travels rearwardly along the conveyer belt 8 beneath a brushing device comprising an endless belt 19 located above and disposed longitudinally of said conveyer belt. Mounted on the outer surface of the belt 19 is a continuous series of longitudinally spaced brushes 20 that are set in blocks 21 rigidly secured to said belt. The rear end of the belt 19 is supported on and driven by a pair of cone driving pulleys 22 fixed to a horizontal cross-shaft 23 whose ends are supported in suitable bearings 24 provided therefor in the side rails 1 of the frame C. These cone pulleys are arranged with their beveled surfaces converging inwardly towards each other; and the inner surface of the endless brush supporting belt 19 is provided with a continuous series of longitudinally spaced drive blocks 25, whose ends are beveled to fit between and frictionally engage the beveled faces of said pulleys at the outer peripheral margins thereof. The front end of the brushing belt passes around a pair of driven cone pulleys 26 that are fixed to a drive shaft 27 whose ends are supported in

suitable bearings 28 provided therefor in the side rails 1 of the frame. These bearings are adjusted longitudinally of the frame to vary the tension of the belt by means of adjusting screws 29. The 5 tapered end surfaces of these pulleys face each other and converge inwardly to snugly receive the tapered drive blocks 25 of the tape brushing belt.

The brushes 20 on the rearwardly moving lower stretch of the belt 19 are pressed downwardly 10 into engagement with the tape A on the upper surfaces of the boxes as they are carried rearwardly on the upper stretch of the conveyor belt 8 by means of a series of pressure rolls 30 that are disposed cross-wise of the frame C and are spaced 15 apart longitudinally thereof between the front and rear brushing belt pulleys 22 and 26. These rollers bear against the upper surfaces of the drive blocks 25 on the lower stretch of the brushing belt 19 during the travel of said stretch beneath said rollers. These rollers are rotatably 20 supported at their ends on journals 31 fixed to the lower ends of vertically disposed rods 32 that extend through aligned openings provided therefor in the top and bottom flanges of the side rails 1 of the frame. The rolls 30 are pressed downwardly into engagement with the drive blocks 25 of the lower stretch of the brushing belt by means of coil compression springs 33 that are sleeved on the rods between upper spring seats 34 that are 25 sleeved on said rods and abut against a bearing strip 35 secured to the undersides of the top flanges of the side rails 1 of the frame. The lower ends of these springs bear against spring seats 36 that are sleeved on said rods and are adjusted 30 longitudinally thereof by means of nuts 37 threaded thereon. The rods 32 are provided below the nuts 37 with stop collars 38 that seat on bearing strips 39 that are supported on the bottom flanges of the side rails. These stop collars 40 serve to limit the downward movement of the spring pressed rods 32.

The upper stretch of the conveyor belt and the lower stretch of the brushing belt preferably travel in the same direction and at different 45 speeds in order to obtain a brushing action of the brushes 20 over the tape A. As shown in the drawings, the conveyor belt pulleys 9 and 10 are of smaller diameter than the brushing belt pulleys 22 and 26, whereby the conveyor belt travels at a 50 higher speed than the brushing belt. The driving pulleys 9 of the conveyor belt are driven by a sprocket chain 40, which passes over a sprocket wheel 40a secured to the driving pulley shaft 11; and the driving pulleys for the brushing belt are 55 likewise driven by a sprocket chain 41 that passes over a sprocket wheel 42 fixed to the driving pulley shaft 23.

In cases where the tape is affixed to the article by a machine such, for instance, as a taping machine of the kind shown in my application filed 60 concurrently herewith, the tape smoothing machine is placed with its receiving end in position to receive the taped articles as they are discharged from the delivery rolls 43 of the taping machine 65 and the two belts of said tape smoothing machine are driven from the lowermost discharge roll shaft of said tape affixing machine preferably by means of an endless sprocket chain 44 that passes over a sprocket wheel 45 fixed to said shaft and over a 70 sprocket wheel 46 fixed to a shaft 47 having a pair of cone pulleys 48 thereon that are connected by means of a V-belt 49 to a pair of cone pulleys 50 on a shaft 51 having a sprocket wheel 52 fixed thereto for driving the sprocket chain 40 which 75 drives the conveyor belt 8. The shaft 47 is also

provided with a gear 53 which meshes with a gear 54 fixed to a shaft 55 located thereabove and provided with a pair of cone pulleys 56 which drive the V-belt that passes over a pulley 57 fixed to a shaft 58 having a sprocket wheel 59 thereon for driving the drive sprocket chain 41 for the brushing belt 19.

The drive pulleys on the shafts 47 and 55 are in the form of cones that are adjustable axially of the shafts to obtain a change speed drive. This 10 type of drive, which is known as a Reeves drive, is well known and it is considered unnecessary to illustrate it in detail. By incorporating these Reeves drive mechanisms in the driving connection in the automatic taping machine and the tape 15 smoothing machine, the speed of the smoothing machine may be regulated to operate in proper timed relation with the automatic taping machine and the relative speeds of the brushing and conveying belts may be regulated to obtain the desired 20 brushing action.

The hereinbefore described tape smoothing machine has several important advantages. It may be readily adapted for use in smoothing tape that is affixed to boxes either by hand or by automatic 25 taping machines. The relative speeds of the conveyor and brushing belts may be regulated for the time required for the adhesive to dry, to obtain the proper brushing action required to eliminate wrinkles and bubbles and to make the brushing 30 machine operate in proper timed relation with the automatic taping machine. The weight initially applied to the tape by the rollers at the receiving end of the machine serves to set the tape before it is engaged by the brushes; and the 35 pressure of the brushes on the tape may be regulated by adjusting the springs of the spring-pressed, drive block engaging pressure rolls.

Obviously, the hereinbefore described machine admits of considerable modification without departing from the invention. Therefore, I do not 40 wish to be limited to the precise construction or article shown and described.

What I claim is:

1. A machine of the kind described comprising 45 an endless conveyer, an endless belt located above and disposed longitudinally of said conveyer, brushes mounted on the outer surface of said belt in position to engage an article on said endless conveyer, means for driving said endless conveyer, and belt in the same direction but at different speeds, and means for varying the speed relationship between said endless conveyer and belt.

2. A machine of the kind described comprising 50 a conveyer, an endless belt located above and disposed longitudinally of said conveyer, members movable with said belt and adapted to engage an article on said conveyer, and means for driving said conveyer and said endless belt in the same direction but at different speeds, pressure rolls located above the receiving end of said conveyer in advance of the corresponding end of said belt in position to bear against the article on said conveyer.

3. A machine of the kind described comprising 55 an article supporting conveyer, an endless belt located above and disposed longitudinally of said conveyer, brushes mounted on the outer surface of said belt in position to engage an article on 70 said conveyer, means for driving said conveyer and said endless belt in the same direction but at different speeds, and floating pressure rolls located above the receiving end of said conveyer in advance of the corresponding end of said belt 75

in position to bear against the article before its engagement by said brushes.

4. A machine of the kind described comprising an article supporting conveyer, an endless belt located above and disposed longitudinally of said conveyer, brushes mounted on the outer surface of said belt in position to engage an article on said conveyer, means for driving said conveyer and said endless belt in the same direction but at different speeds, and spring-pressed rolls journaled on said machine and adapted to yieldably hold said brushes in engagement with said article.

5. A machine of the kind described comprising an article supporting conveyer, an endless belt located above and disposed longitudinally of said conveyer, brushes mounted on the outer surface of said belt in position to engage an article on said conveyer, means for driving said conveyer and said endless belt in the same direction but at different speeds, spring-pressed rolls journaled on said machine and adapted to exert a downward pressure on the lower stretch of said endless brush carrying belt.

6. A machine of the kind described comprising an article supporting conveyer, an endless belt located above and disposed longitudinally of said conveyer, brushes mounted on the outer surface of said belt in position to engage an article on said conveyer, means for driving said conveyer and said endless belt in the same direction but at different speeds, vertically movable rolls journaled in said machine and adapted to engage the lower stretch of said endless brush carrying belt, means for yieldably resisting the upward movement of said rolls, and means for varying such resistance.

7. A machine of the kind described comprising an article supporting conveyer, an endless belt located above and disposed longitudinally of said conveyer, members mounted on said belt in position to engage an article on said conveyer, means for driving said conveyer and said endless belt in the same direction but at different speeds, pairs of cone pulleys mounted in said machine for supporting said endless belt, the pulleys of each pair being disposed with their tapered surfaces converging inwardly towards each other, and drive blocks secured to the inner face of said belt and adapted to frictionally engage the converging tapered surfaces of said cone pulleys.

8. A machine of the kind described comprising an article supporting conveyer, an endless belt located above and disposed longitudinally of said conveyer, brushes mounted on the outer surface of said belt in position to engage an article on said conveyer, means for driving said conveyer and said endless belt in the same direction but at different speeds, spring-pressed rolls journaled in said machine and adapted to exert a downward pressure on the lower stretch of said endless brush carrying belt, pairs of cone pulleys mounted in said machine for supporting said endless belt, the pulleys of each pair being disposed with their tapered surfaces converging inwardly towards each other, and drive blocks secured to the inner face of said belt and adapted to frictionally engage the outer peripheral portions of the converging surfaces of said cone pulleys.

70 9. A machine of the kind described compris-

ing an article supporting conveyer, an endless belt located above and disposed longitudinally of said conveyer, brushes mounted on the outer surface of said belt in position to engage an article on said conveyer, means for driving said conveyer and said endless belt in the same direction but at different speeds, spring-pressed pairs of cone pulleys mounted in said machine for supporting said endless belt, the pulleys of each pair being disposed with their tapered surfaces converging inwardly towards each other, and drive blocks secured to the inner face of said belt and adapted to frictionally engage the outer peripheral portions of the converging surfaces of said cone pulleys, rolls adapted to exert a downward pressure on the drive blocks on the lower stretch of said endless brush carrying belt, and vertically movable hanger rods rotatably supporting said rolls.

10. A machine of the kind described comprising an endless article conveyer belt, a second endless belt located above and disposed longitudinally of said conveyer belt, brushes mounted on the outer surface of said second belt in position to engage an article on said conveyer belt, means for driving said conveyer and said endless belt in the same direction but at different speeds, pairs of cone pulleys mounted in said machine for supporting said second belt, the pulleys of each pair being disposed with their tapered surfaces converging inwardly towards each other, drive blocks secured to the inner face of said second belt and adapted to frictionally engage the outer peripheral portions of the converging surfaces of said cone pulleys, rolls adapted to engage the drive blocks on the lower stretch of said second belt, vertically movable hanger rods supporting said rolls, springs for yieldably resisting the upward movement of said hanger rods, and means for adjusting the tension of said springs.

11. A machine of the kind described comprising an article supporting conveyer, an endless belt located above and disposed longitudinally of said conveyer, brushes mounted on the outer surface of said belt in position to engage an article on said conveyer and said endless belt in the same direction, power driven means for affixing adhesive tape to said articles and delivering them onto the receiving end of said conveyer, and a driving connection between said power driven means and said conveyer and said endless belt including means for varying the speed relationship between said conveyer and said belt and between said conveyer and belt and said power driven tape affixing and article feeding means.

12. A machine of the kind described comprising an endless article supporting conveyor, an endless belt located above and disposed longitudinally of said conveyor, brushes mounted on the outer surface of said belt in position to engage an article on said conveyor, means for driving said conveyor and said endless belt in the same direction but at different speeds, and means mounted on said machine and adapted to engage the lower stretch of said endless belt to yieldably hold the brushes on said stretch in engagement with the article on said conveyor.
